UNITED STATES PATENT OFFICE.

WILLIAM H. FRIEDLINE, OF MEYERSDALE, PENNSYLVANIA, ASSIGNOR TO MODERN-OLA COMPANY, OF JOHNSTOWN, PENNSYLVANIA, A CORPORATION OF PENNSYLVANIA.

PHONOGRAPH CONSTRUCTION AND ILLUMINATION.

1,369,735.

Specification of Letters Patent. Patented Feb. 22, 1921.

Application filed November 21, 1919. Serial No. 339,709.

To all whom it may concern:

Be it known that I, WILLIAM H. FRIEDLINE, a citizen of the United States, residing at Meyersdale, in the county of Somerset and State of Pennsylvania, have invented new and useful Improvements in Phonograph Construction and Illumination, of which the following is a specification.

The general object of my present invention is the provision of a phonograph cabinet so constructed and equipped, that access may be readily gained to any part of a record and the parts that coöperate therewith, and the record and the coöperating parts may be thoroughly illuminated, the latter conduced to ready placing and removal of the record and the convenient and accurate positioning of the style relatively to the record.

To the attainment of the foregoing, the invention consists in the improvement as hereinafter described and definitely claimed.

In the accompanying drawings, hereby made a part hereof:

Figure 1 is a vertical section showing sufficient of a cabinet to illustrate one embodiment of my invention.

Fig. 2 is a plan view of the same.

Fig. 3 is a view, partly in section and partly in elevation, taken at right angles to Fig. 1.

Fig. 4 is an enlarged detail view of a portion of the improvement.

Fig. 5 is an enlarged detail section showing the connection of the lamp post to the diametrical bar.

Similar numerals of reference designate corresponding parts in all of the views of the drawings.

The cabinet body 1 is preferably of cylindrical form, and on the same is superimposed and fastened a motor board 2. Superimposed and fastened, in turn, on the motor board 2, is an annular member 3 that constitutes a motor board rim, and fixed to the inner side of the motor board 3 and resting on the motor board 2 are diametrically opposite brackets 4. Arranged on and fixed to the brackets 4 is a diametrical bar 5, the ends of which are extended beyond said brackets 4, and interposed between and secured to the motor board rim 3 and the end portions of the bar 5 are filler blocks or pieces 6 which correspond in width to the bar 5. Hinged to the opposite sides of the

bar 5 are lids 7, and carried by the said lids are arcuate flanges 9 which are adapted, when the lids are closed, to rest in superimposed relation upon the rim 3. It will be noticed in this connection that when the lids 7 are closed, the filler blocks 6 will close the space between the ends of the flanges 9, so that the closure will be complete entirely around the upper portion of the cabinet, and this in a neat and finished manner.

The diametrical bar 5 is provided at its center with a vertically disposed aperture 10 in which is socketed the reduced lower end 11 of a tubular post 12, preferably of wood that bears on and rises from the bar 5.

Arranged upon the upper end of the said tubular post 12 is an electric lighting fixture 13 that carries, by preference, a plurality of incandescent lamps 14.

Extending through the bore of the post 12 is a pipe section 15, that is threaded at its lower and upper ends; the lower threaded end being for the engagement of a nut 16 between which and the under side of the bar 5 a washer 17 is interposed, and the upper threaded end being for the engagement of a nut 18 that serves to clamp the fixture 13 against the upper end of the post 12, and also serves for the passage of the wires in electrical connection with the filaments of the lamps 14. The said wires, indicated by 19, are carried from the fixture 13 through the pipe section 15 and are connected at 20 to a plug for coöperation with a socket 21 on the motor board 2 at a point adjacent to the wall of the body 1; the said socket 21 being connected with a conduit 22 that extends downwardly from the motor board 2.

It will be manifest from the foregoing, that the nuts 16 and 18 in combination with the pipe section 15, will serve to effect a strong and rigid connection of the post 12 to the bar 5, and at the same time the pipe section 15 will reinforce and brace and strengthen the post 12 throughout the length thereof, and consequently there will be little or no liability of the said post 12 becoming loose during the use of the cabinet.

It will also be apparent that by reason of the relative arrangement of the electric lighting fixture, the motor board 2 above which the rotary record table 25 is located, and the lids 7, the opening of the lids will be attended by thorough illumination of the

record on the table, so that the style on the tone arm (not shown) may be quickly and accurately placed relatively to the record, and may as readily be removed therefrom 5 at the end of the playing of a record.

My novel construction is further practically advantageous, inasmuch as it is strong and durable, and at the same time lends itself to the production of a cabinet that is 10 highly finished in appearance.

Having described my invention, what I claim and desire to secure by Letters Patent, is:

1. The combination in a cabinet, of a cylindrical body, a motor board superimposed thereon, an annular motor board rim arranged on the motor board, diametrically opposite brackets arranged on the motor board, and at the inner side of the rim and 15 extending above the latter, a diametrical bar superimposed upon the brackets and extending outwardly beyond the same and having a central vertical aperture, filler blocks arranged at the outer sides of the 20 brackets and interposed between the motor board rim and the diametrical bar, lids hinged to opposite sides of the diametrical bar and having arcuate flanges adapted 25 when the lids are closed to bear on the rim with their ends opposed to the side edges of 30 the filler blocks, a tubular lamp post bearing on and rising from the diametrical bar and having a reduced lower end socketed in the aperture of the bar, a lighting fixture arranged on the upper end of said post, a pipe 35 section arranged in and extending above and below the post and threaded at its opposite ends, clamping means threaded on said pipe section above the lighting fixture, and 40 clamping means threaded on said pipe section below the diametrical bar.

2. A phonograph cabinet having a motor board and a rotary record table above same and also having above the motor board and 45 the record table and in spaced relation thereto a cross-bar, lids hinged to opposite sides of said cross-bar, a post fixed with respect to and rising from the cross-bar, and a lamp carried on the upper portion of the 50 post, the said lids when raised permitting of illumination of the upper portion of the cabinet.

3. A phonograph cabinet having a motor board above which is arranged a rotary record table and also having above the motor board and the record table and in spaced 55

relation thereto a cross-bar, lids hinged to opposite sides of said cross-bar, a post fixed with respect to and rising from the cross-bar; said post being tubular, a threaded pipe section extending through the post, a lighting fixture on the post, clamping means threaded on the pipe section to hold the fixture against the upper end of the post, and threaded clamping means on the lower end 60 of the pipe section to hold the post downwardly against the cross-bar.

4. In a phonograph cabinet, the combination of a motor support mounted in the upper end of said cabinet, a rotary record table mounted on said support, a partial closure for the upper end of said cabinet fixed thereto and spaced above said table to permit the insertion of records, a lamp support mounted on said fixed closure to illuminate 70 said table and a second partial closure for the upper end of said cabinet complementary to said fixed closure and hinged thereto to swing in a vertical plane, said partial closure when raised permitting of illumination 75 of the upper portion of the cabinet.

5. In a phonograph cabinet, the combination of a motor support mounted in the upper end of said cabinet, a rotary record table mounted on said support, a partial closure for the upper end of said cabinet fixed thereto and spaced above said table to permit the insertion of records, a vertical lamp post mounted on said fixed closure, a lighting fixture on the upper end of said 80 lamp post to illuminate said record table, and a second partial closure for the upper end of said cabinet complementary to said fixed closure and hinged thereto to swing in a vertical plane underneath said lighting fixture, said partial closures when raised permitting of illumination of the upper portion 85 of the cabinet.

6. A phonograph cabinet having a motor support mounted in the upper end of said cabinet and a rotary record table mounted on said support and also having a closure characterized by a portion fixed with respect to the cabinet, a lamp supporting member on said portion and carried thereby, 100 and a closure portion connected with said fixed portion and movable to and from a closed position; said closure portion when raised permitting illumination of the upper portion of the cabinet.

In testimony whereof I affix my signature.
WILLIAM H. FRIEDLINE.
